Term of patent 14 years

(Cl. D34—5)

FIG. 1

FIG. 2

FIG. 1 is a perspective view of a game board embodying my new design, the playing surface of the game board being shown essentially in plan; and

FIG. 2 is a section taken substantially along the line 2—2 of FIG. 1.

The characteristic feature of my design resides in the combination on the cruciform patterned game board disclosed of a multi-colored central cross and peripheral pathways colored conformably with adjacent portions of the central cross, together with the specifically shaped starting areas, all as shown.

I claim:

An ornamental design for a game board, as shown and described.
